UNITED STATES PATENT OFFICE.

CYRUS LOMBARDI, OF CONEY ISLAND, AND JACOB MARCUS, OF EAST NEW YORK, N. Y.

BLINDSTITCHING ATTACHMENT FOR SEWING-MACHINES.

1,314,820.

Specification of Letters Patent.

Patented Sept. 2, 1919.

Application filed July 5, 1917. Serial No. 178,608.

To all whom it may concern:

Be it known that we, CYRUS LOMBARDI and JACOB MARCUS, subject of the King of Italy and citizen of Russia, respectively, residing at Coney Island, in the county of Kings and State of New York, and at East New York, in the county of Kings and State of New York, respectively, have invented certain new and useful Improvements in 10 Blindstitching Attachments for Sewing-Machines, of which the following is a full, clear, concise, and exact description.

Our invention relates to an attachment for sewing machines, and particularly to a mechanism for sewing a blind stitch.

The object of the invention is to provide such a mechanism that may be readily attached to the presser-foot bar of a sewing machine, and be adjusted thereon to perform all the functions relating to the guiding of the material to be sewed in a simple and expeditious manner, and without the aid of any guide plates or attachments on the bed plate of the machine.

The invention consists in general of a presser-foot provided with guide flanges, which may be manipulated and adjusted thereon so that a variety of thicknesses of material may be sewed, and so that the needle 25 may penetrate the upper layer of the material to any desired depth.

In the accompanying drawing, Figure 1 is a perspective view of the mechanism as attached to the presser-foot bar; Fig. 2 is a cross-section of the mechanism taken on line 2-2 of Fig. 1; and Fig. 3 is a fragmentary front view of the mechanism taken on the line 3-3 of Fig. 1, showing in cross-section two layers of the material to be sewed together.

Referring to Fig. 1 the presser-foot 1 is attached to the presser-foot bar 2 of an ordinary sewing machine. This presser-foot consists of the body portion 3 and the foot 45 or flange 4, linked at 5 so as to press against the material in slightly yielding fashion. Mounted on presser-foot 1 is a guide block 6, by means of the projecting shanks 7 and 7' thereof engaging grooves 8 and 8' on the 50 foot 1. This guide block 6 is adjustable in a horizontal direction by means of the screw 9, rotatably fastened on presser-foot 1 by plate 10 and entering into the body of the block 6. The block 6 may be permanently 55 fixed in any desired relation to presser-foot 1 by the screw 12, which clamps the two

parts together, by being screwed into the body portion 3 of the presser-foot 1, and by having the head thereof with the washer 13 overlapping the edge of the projecting shank 60 7 in which a slot 14 is cut to limit the extent to which the block 6 may be moved away from presser-foot 1.

Yieldingly mounted on the block 6 is a guide-member 16, by means of the shank 17 65 entering into a slot 18 on the block 6 and by having a slot 19 cut therein through which a pin 20, fixed on block 6, is passed. A spring 21 is inserted in a vertical hole 22 in the guide member 16 between the pin 20 and 70 the bottom of hole 22, to hold the guide member 16 in a downward position. This member 16 has a forward projecting foot or flange 23 lying parallel with but in a plane at right angle to the foot or flange 4. The 75 cover plate 25, fixed on the side of the guide block 6, is provided with a slot (not shown) through which the stud 27 is passed and held in the shank 17 of guide member 16. This stud 27 may be used by the operator to 80 lift the guide member 16 in a vertical direction. Mounted fixedly on the guide-member 16 is the mounting block 29, by means of screw 30 and dowel pin 31. (See Fig. 1). The guide flange or foot 32 which lies parallel with flange 23 is provided with a right-angle round-projecting pin 33 that enters in hole 34 in block 29. The flange 32 is movable in a horizontal direction by movement of the pin 33 horizontally in the hole 34 and 90 vertically by rotation of the pin 33 in the hole 34, the flange 32 being by this means adjustable in a horizontal and vertical relation to the flange 23. The flange 32 may be fixed permanently in block 29 by means of 95 the screw 35.

The operation of the mechanism is as follows: The presser-foot 1 is lowered in the usual manner and the material is placed on the bed plate 36 with the edge of the 100 under-layer 37 the desired distance to the right from the presser-foot 1. This distance is determined by flange 32 which may be shifted to the right or left, depending on the width of the over-lapping edge desired on the under layer 37 in relation to the upper layer 41. This flange 32 may also be pressed down against the bed-plate 36 so as to insure a good firm guide against which the edge of the under-layer 37 may 110 run when passed along by the operator. Under certain circumstances it may be de-

sirable not to use this guide 32, and the block 29 may then be entirely removed from guide member 16 by unscrewing the mounting screw 30. Then again it may be desir-
5 able to only temporarily dispense with the use of the guide 32, and it may then be turned out of the way of the under layer 37 by rotating it with the knob 40 and clamping it in such a position by screw 35.
10 The upper layer 41 that is to be blind-stitched to the under-layer 37 on the table is folded and passed underneath the presser-foot with the fold pressed against the vertical guide plate 23, which has been ad-
15 justed in a horizontal direction away from the flange 4, according to the depth that it is desired to have the blind stitch penetrate the upper-folded layer 41. The guide plate 23 of guide member 16 yieldingly adjusts
20 itself in a vertical direction, in accordance with the thickness of the under layer 37, and presses this layer tightly against the bed plate 36. The machine is now set in motion and the two layers of material are
25 in position to be stitched together by being passed forward by the operator and guided by the flanges 4, 23 and 32. During the stitching the flanges 4 and 23 first engage the fold in the upper layer 41 loosely as it
30 is fed by the operator, and later, press it more tightly together, and the needle will therefore penetrate the upper layer 41 at exactly the right distance from the edge of the fold and the flange 32 will guide the
35 under layer 37 so that the upper layer 41 will be stitched to the under layer 37 at exactly the right position.

Although we have described a particular form of our invention, it may be constructed
40 in a variety of manners without departing from its scope, and it is therefore limited only by the appended claims.

What is claimed is:

1. In combination with a presser-foot bar
45 of a sewing machine, a presser-foot mounted thereon, a horizontal flange yieldingly secured to said presser-foot, a vertical flange adjustable in a horizontal and yielding in a vertical direction in relation to the horizontal flange, means for permanently fixing

said vertical flange in any desired horizontal relation to said horizontal flange, and a second vertical flange adjustable in a horizontal and vertical direction in relation to said first-named vertical flange. 55

2. In combination with a presser-foot bar of a sewing machine, of a presser-foot mounted thereon, a horizontal flange secured to said presser-foot adapted to yieldingly press together the materials to be
60 stitched, a vertical flange against which the fold in the upper layer of the material is placed, a mounting block for said vertical flange mounted on the presser-foot, a spring for pressing said vertical flange against the
65 under layer of the material, a screw for moving said mounting block to adjust the vertical flange in a horizontal relation to the horizontal flange, a screw for permanently clamping said mounting block to said
70 presser-foot, a second vertical flange against which the edge of the under-layer of material is placed, a mounting block for said second vertical flange mounted on said first-mentioned vertical flange, and a screw for
75 permanently clamping said second flange on said block in any desired relation to the first vertical flange.

3. In combination with a presser-foot bar
80 of a sewing machine, of a presser-foot mounted thereon, a horizontal flange yieldingly secured to said presser-foot shaped so as to press the fold of the upper layer of the material to be stitched tightly at the point where the needle penetrates the edge
85 of the fold, a guiding means mounted on the presser-foot, adjustable in relation to the horizontal flange horizontally and vertically, means for securing said guiding means
90 in a fixed horizontal relation to the horizontal flange and in a yielding vertical relation to the under layer of the material, and guiding means mounted on said first-mentioned guiding means adjustable in relation thereto horizontally and vertically. 95

In witness whereof, we hereunto subscribe our names this 27 day of June, A. D., 1917.

CYRUS LOMBARDI.
JACOB MARCUS.
